ANCHORING STRUCTURE FOR PORTABLE
ICE BOXES

William F. Kirk, Kansas City, Mo.

Application December 17, 1937, Serial No. 180,360

1 Claim. (Cl. 248—361)

This invention relates to ice boxes of the portable, transportable type which are used in shipping small quantities of perishables in freight cars that are not necessarily equipped to maintain a desired low temperature therein, and the primary object of this invention is to provide in such an ice box means for anchoring the same in place in the freight car so that accidental movement will not occur while the car is traveling.

One of the important objects of this invention is the provision of anchoring structure for portable ice boxes that cooperates with the wheels on the ice box in such manner as to positively render the wheels inoperative when the anchoring structure is in place.

A yet further aim of this invention is the provision of anchoring means for portable, transportable ice boxes that permits moving the block receiving element to an inoperative position so that the wheels may freely function while the ice box is being moved through their use.

This invention further provides a unique ice box and means for anchoring the same in place, which includes specially formed legs at one end of the ice box and movably mounted elements at the other end of said box, which movable elements are in juxtaposition to a series of wheels carried by the box along the said second mentioned end.

Another object of the invention is to provide a specially formed anchoring element for portable ice boxes which element has a block receiving cavity formed therein, and a specially located slot in communication with said cavity so that the block when in place, may be secured to the supporting surface at a point within the cavity as well as at points remote therefrom.

Other objects of the invention will appear during the course of the following specification, referring to the accompanying drawings wherein:

Figure 1 is a perspective view of a portable ice box illustrating the manner of incorporating the anchoring structure at one end thereof.

Fig. 2 is a similar perspective view of the other end of the ice box showing the anchoring structure in place.

Fig. 3 is an enlarged fragmentary vertical sectional view through the lower portion of the ice box.

Fig. 4 is a still further enlarged fragmentary detailed view illustrating the two positions assumed by one of the movable block receiving elements of the anchoring structure.

Fig. 5 is a fragmentary vertical sectional view taken along line V—V of Fig. 4 and,

Fig. 6 is an enlarged fragmentary vertical sectional view taken along line VI—VI of Fig. 1.

In practice it has been found that portable ice boxes of the nature provided for transporting relatively small quantities of perishables, are hard to anchor in place so that the jolting of the freight car will not dislodge the ice box and cause damage to the box itself and to the freight loaded in the car with the same. Ice boxes wherein perishables are shipped, and which are movable to and from a position in a freight car, comprise an insulated box 8 having a cavity 10 therein for the reception of the merchandise to be shipped. Conventional doors 12 permit access to cavity 10 and box 8 is partially supported by a series of wheels 14 mounted on an axle 16 which is carried by a series of bearing brackets 18. These wheels 14 are positioned adjacent to one end of box 8. This said one end is preferably, the rear end thereof when it is considered that the doors 12 are in the front end of the box.

In actual construction, wheels 14, brackets 18 and the associated structure is carried by an angle iron frame 20 upon which sits box 8. The forward end of box 8 has a leg 22 near each corner thereof, and this leg carries a specially formed element 24 that is analogous in nature to movable element 26 mounted at the rear end of box 8 and adjacent to wheels 14.

As illustrated in Fig. 1, box 8 is moved by fitting a small hand truck 28 thereunder so that the forward end is raised from the supporting surface 30 a sufficient distance to render legs 22 and elements 24 ineffective as supporting parts. When this truck 28 is in the operative position so that legs 22 are raised from supporting surface 30, wheels 14 combine with the wheels of truck 28 to permit movement of the box as desired. When the box is located within a freight car and blocking to prevent movement is performed, element 24 is secured to supporting surface 30 by a block 32, one end of which is extended over slotted floor 34 of element 24. Slot 36 formed through floor 34 permits the passage of a large spike or analogous fastening means 38, a similar one of which may likewise be driven into supporting surface 30 exteriorly of element 24.

Side walls 40 of elements 24 will bear against opposite sides of block 32 to prevent sidewise movement of box 8 and elements 22 and 24 respectively, will be held down against surface 30, to effectively and further preclude longitudinal or transverse displacement of box 8.

Element 24 is secured directly to leg 22 so that it becomes an integral part thereof and in the

instance illustrated, the connection between these parts is by welding along the sides as illustrated at 42.

From the foregoing, it will be clear that the forward end of box 8 may be effectively secured to supporting surface 30 and while elements 26 mounted on box 8 at the other end thereof, are of the same general character as elements 24, they are novel to the extent of being movable 10 to and from a position against supporting surface 30.

Reference to Figs. 4 and 5 will teach that elements 26 are likewise provided with a cavity which is formed between backwall 44, side walls 15 46, and bottom wall 48. Wall 48 has a slot 50 formed therethrough for the reception of a spike or analogous means, 52, which is passed through block 54 when box 8 is anchored against movement. Back wall 44 has a slot 56 formed there- 20 through that is of a special nature in that the end portions thereof are squared as at 58 while the central portion 60 thereof is enlarged to permit the entire element 26 to be rotated about bolt 62 when the latter is in axial alignment with portion 60 of slot 56. This bolt 62 has a squared 25 length 64 provided thereon and the shouldered nature of bolt 62 precludes its being drawn against element 26 during assembly—thus element 26 is free to reciprocate a distance approxi- 30 mately equal to the length of slot 56 and to rotate about the center of bolt 62 when this bolt is passing through portion 60.

The squared end portions 58 of slot 56 are of a 35 width substantially the same as the width of square length 64 of bolt 62 and therefore when the bolt is in squared end of slot 56, element 26 cannot turn. Such a relation of parts as just 40 aforementioned, allows the movement of element 26 from the position against supporting surface 45 30 (shown in full lines of Figs. 4 and 5) to an inoperative or raised position, shown in dotted lines of Figs. 4 and 5. When box 8 is being moved from place to place, elements 26 must be rendered inoperative and manipulated so that they will not interfere with the movement of the box when truck 28 is brought into play.

The relation of blocks 54 to these rear elements 26 is the same as the relation of block 32 to forward elements 24 in that movement in any 50 direction is precluded when the block is secured in place as illustrated in Fig. 5.

Elements 26 are secured directly to frame 20 of the box through the medium of bolts 62 and

the entire assembly should be constructed of strong material such as steel, so that severe stresses and strains are definitely overcome.

Obviously the greater the weight of the box and material therein, the greater will be the friction between forward legs and elements 24 and supporting surface 30, and the proximity of elements 26 to wheels 14 will always insure that these wheels are rendered inoperative when blocks 54 are in place.

It is conceivable that anchoring structure for portable ice boxes may be made to present different physical characteristics than those illustrated and described, and it is desired to be limited only by the scope of the appended claim.

Having thus described the invention, what is claimed as new and desired to be secured by Letters Patent is:

In a portable ice box having wheels on the bottom thereof for moving the same along a supporting surface, anchoring structure for securing the ice box in place, comprising an element consisting of a slotted backwall disposed in a vertical plane against one side of the ice box, a slotted bottom wall disposed in a horizontal plane 25 against the supporting surface when the element is in the operative position, and side walls cooperating with said backwall and the bottom wall to form a block-receiving cavity; and a bolt having a head and a squared shank thereon carried by the ice box and extending through the slot in said backwall, said slot having a central enlarged portion intermediate its ends to permit turning said element about the axis of said bolt when the latter is extended through the enlarged portion, the slot on each side of the enlarged portion being narrower than the enlarged portion and substantially the same width as the squared shank of the bolt to hold the element against accidental rotary movement when the squared shank is in the slot on either side of the enlarged portion, the location of said slot and the bolt being such as to allow the bottom wall of the element to rest upon the supporting surface when the wheels of the ice box are resting on the surface and with the bolt against the end of the slot above and at one side of the enlarged portion thereof or to permit the element to be rotated 180° and slide over the bolt until the squared shank is positioned adjacent the end of the slot 50 on the other side of said opening.
